FIG. 1 is a side elevational view of a motorcycle trailer showing my new design in closed condition;

FIG. 2 is a top plan view thereof;

FIG. 3 is a rear elevational view thereof;

FIG. 4 is a side elevation view thereof opposite to that shown in FIG. 1;

FIG. 5 is a side elevational view thereof on a reduced scale in open and extended condition;

FIG. 6 is a front elevational view of FIG. 5;

FIG. 7 is a side elevational view opposite to that shown in FIG. 5;

FIG. 8 is a top plan view of FIG. 5; and

FIG. 9 is a rear elevational view of FIG. 5.

The fragmentary criss-cross pattern shown in FIGS. 5, 6 and 7 is representative of screening and is understood to be continuous throughout the areas shown.

I claim:

The ornamental design for a motorcycle trailer, as shown and described.
